Specification for Design.

Patented Jan. 3, 1922.

Application filed February 19, 1921. Serial No. 446,522. Term of patent 14 years.

To all whom it may concern:

Be it known that I, WILLIAM C. HICKOX, a citizen of the United States, residing at Rochester, in the county of Monroe and State of New York, have invented a new, original, and ornamental Design for a Bottle for Fire Extinguishers, of which the following is a specification, reference being made to the accompanying drawing, in which:

Figure 1 is a top plan view of a bottle for fire extinguishers, showing my new design.

Fig. 2 is a side elevation of the same.

I claim:

The ornamental design for a bottle for fire extinguishers, as shown.

WILLIAM C. HICKOX.
